UNITED STATES PATENT OFFICE.

CHRISTY RICARD, OF WOONSOCKET, RHODE ISLAND.

SELF-THREADING SHUTTLE.

Application filed October 4, 1926. Serial No. 139,358.

This invention relates to an improved self-threading shuttle for looms and more particularly to a shuttle of this character having means for positively preventing the removal of the thread from either end of the thread passage when the shuttle is in use.

While various means have been employed heretofore in the construction of self-threading shuttles for preventing the removal of the thread from the thread passage none of these devices has proved entirely successful, since a loose bobbin may overrun to produce a thread loop at the bobbin end of the thread passage or the thread may be caused to loop at the tip end of the passage as the bobbin contacts with the picker stick whereby the thread may be thrown from the passage at either end thereof. In the previous constructions of this character only one positive thread lock has been provided thus in all cases permitting the thread to be thrown from one end of the passage where it may be caught upon some projecting part and broken by further movement of the bobbin or even detached from the single locking means employed.

It is the object of the present invention to provide a shuttle of this character which will permit self-threading and positively lock the thread against removal from the thread receiving passage. In the accomplishment of this object a positive thread locking means is provided at each end of the thread passage thus preventing the removal of the thread from any portion of the passage during the operation of the shuttle.

Other objects and advantages of the invention relate to various structural details and modes of operation as will be more fully set forth in the detailed description to follow.

Referring to the drawings:

Fig. 1 is a perspective view of a self-threading shuttle embodying the present invention,

Fig. 2 is a cross sectional view taken along the line 2—2 of Fig. 1 and showing the construction of the thread locking means located at the bobbin end of the thread receiving passage, and,

Fig. 3 is a perspective view of the thread block showing the thread passage and the thread locking means located adjacent to the shuttle tip.

The shuttle body 1 is of the usual construction and has a bobbin chamber 2 in which the bobbin 3 carrying the thread 4 is detachably

supported, as is usual in devices of this character.

Forwardly of the bobbin chamber 2 the shuttle is provided with a thread receiving passage 5 which extends through a thread block 6, preferably of metal, the thread receiving passage communicating with a side delivery eye 7 through which the thread passes in the reciprocating movement of the shuttle.

The thread receiving passage 5 of the block 6 may be substantially straight to facilitate drawing the thread into the passage on the first pick of the shuttle after replenishment.

A curved thread lock 8 has one end thereof secured in the block upon one side of the passage 5 adjacent to the bobbin end of the passage, the thread lock 8 being formed of thin flexible material extending across the passage and curving downwardly so that the free end lies within the groove 10 formed in the wall of the passage.

This construction readily permits the thread to be drawn downwardly within the groove 10 below the end of the curved lock 8 whereupon the flexible character of the lock causes the free end thereof to snap back into the groove after the thread has passed thereover and the thread is positively retained in the passage at this point. The curved tip 11 of the thread block 6 which serves as a thread director to direct the thread into the passage 5 on the first pick of the shuttle after replenishment may be of any suitable shape, and may or may not extend across the passage 5, although in the present case it terminates short of the passage since the thread lock cooperating therewith renders further extension of the curved tip unnecessary.

A thin flexible member 12 has one end secured to the thread block 6 on the opposite side of the passage from the thread directing tip 11 and extends downwardly across the passage 5, the free end of said flexible member contacting with a portion of the thread directing member 11 to readily permit the thread to be drawn downwardly over the thread directing member 11 into the passage 5 but positively preventing removal of the thread from the passage.

It will be understood that on the return movement of the shuttle after replenishment the thread will pass through the side delivery eye 7 adjacent the groove 14 for delivery.

It will be understood that the construction

shown herein readily permits the thread to be drawn into the thread receiving passage on the first pick after replenishment and positively retains the thread in the passage preventing it from being thrown out both at the bobbin end and at the tip end after the thread has passed the free ends of the thread locks 8 and 12. Thus breaking of the thread by reason of its escaping from the thread receiving passage and looping and catching on obstructions is positively prevented.

While the thread block shown is formed with a substantially straight passage 5 and with the thread directing portion or tip terminating short of the passage 5 to facilitate threading, the present improvement may be readily applied to and used with any of the usual types of thread blocks.

What I claim is:

- 20 1. In a self-threading shuttle, a threading block having a longitudinal thread receiving passage, and positive locking means located at opposite ends of said block to prevent the removal of the thread from said passage.
- 25 2. In a self-threading shuttle having a side delivery eye and a passage for the thread, a rigid thread director positioned upon one side of said passage, and a yielding lock extending downwardly from the body of the shuttle diagonally across the passage and into contact with the thread director to normally close the passage and prevent removal of the thread from the passage.
- 30 3. In a self-threading shuttle, a threading block provided with a longitudinal thread passage open at the top for the insertion of the thread, a flexible curved thread lock located within and extending entirely across the effective width of the passage in said block adjacent to one end of said passage, and a

resilient member carried by said block and extending across said passage adjacent to the opposite end of said passage for preventing removal of the thread from said passage.

4. In a self-threading shuttle, a threading block provided with a longitudinal thread receiving passage and having a groove formed in the wall of the passage adjacent to one end of said block, a curved thread lock having one end secured to the block and the opposite end positioned in said groove, and a flexible thread lock at the opposite end of said thread receiving passage.

5. In a self-threading shuttle, a threading block provided with a longitudinal thread receiving passage and having a rigid thread directing portion located adjacent to one side of said passage, and a flexible thread lock secured to said block upon the opposite side of said passage and extending downwardly across said passage and into contact with the thread directing portion of said block.

6. In a self-threading shuttle, a threading block provided with a longitudinal thread receiving passage and having a groove formed in the wall of the passage adjacent to one end of said block, and a curved thread lock extending across the passage having one end secured to the block and the opposite end positioned in the groove to positively prevent the removal of the thread from the passage.

7. In a self-threading shuttle, a threading block having a longitudinal thread receiving passage, and flexible locking members located at opposite ends of said passage for positively preventing removal of the thread from either end of said passage.

In testimony whereof I have affixed my signature.

CHRISTY RICARD.
